CLAIM

The ornamental design for a minimal adjustable car mount as shown and described.

DESCRIPTION

FIG. 1 is a front elevation view of a minimal adjustable car mount in an open position;

FIG. 2 is front elevation view of the minimal adjustable car mount in a folded position;

FIG. 3 is a rear elevation view of the minimal adjustable car mount in an open position;

FIG. 4 is a rear elevation view of the minimal adjustable car mount in a folded position;

FIG. 5 is a side elevation view of the minimal adjustable car mount in an open position;

FIG. 6 is a side elevation view of the minimal adjustable car mount in the folded position;

FIG. 7 is a view of the minimal adjustable car mount in an open position when viewed from the top right;

FIG. 8 is a view of the minimal adjustable car mount in a closed position when viewed from the top right;

FIG. 9 is a top plan view of the minimal adjustable car mount in a closed position; and,

FIG. 10 is a top plan view of the minimal adjustable car mount in a closed position.

The minimal adjustable car mount is symmetrical such that the view from the right side and the view from the left side would be the same other than the relative locations of the front and rear depending upon the side from which the view is taken.

The broken line showing of portions of the minimal adjustable car mount is included for the purpose of illustrating environment and forms no part of the claimed design.
